EXPANSIBLE STOPPER

James L. Whitsel, Denver, Colo.

Application May 29, 1948, Serial No. 29,994

8 Claims. (Cl. 220—24.5)

1

This invention relates to stoppers and plugs for bottles, jugs, drains, and the like, and more particularly to plugs employable for the obstruction and closing of conventional waste lines leading from sinks and lavatories, and has as an object to provide an improved such unit of enhanced efficiency.

A further object of the invention is to provide a removable and replaceable, repetitiously-employable plug or stopper selectively expandable to effectively fill and close an end of a cylindrical passage.

A further object of the invention is to provide an improved stopper or plug selectively adjustable to alternative conditions of minimum, normal diameter and maximum expanded diameter, whereby the unit is adapted for free, non-frictional, initial introduction within the end of a cylindrical passage and subsequent expansion into tightly-fitted, closing relation with said passage.

A further object of the invention is to provide an improved stopper or plug susceptible of selective diametric expansion without recourse to screw threads or cams.

A further object of the invention is to provide an improved construction and operative interrelation of elements constituting a selectively-expandable stopper or plug.

A further object of the invention is to provide a selectively-expandable stopper or plug that is relatively simple and inexpensive of manufacture, positive and efficient in use, convenient of operative manipulation, adapted for production in a variety of sizes and specific embodiments fitted to particular needs, and durable throughout a long life of repetitive use.

With the foregoing and other objects in view, my invention consists in the construction, arrangement, and combination of elements herein-after set forth, pointed out in my claims, and illustrated by the accompanying drawing, in which—

Figure 1 is a cross section taken axially through a simple embodiment of the invention in a relationship of elements productive of plug or stopper expansion. Figure 2 is a section similar to Figure 1 illustrating the relatively-movable elements of the unit in an alternative position productive of plug or stopper normal minimum diameter. Figure 3 is a top plan view of the unit shown in the preceding figures. Figure 4 is a transverse section taken on the indicated line 4—4 of Figure 2. Figure 5 is a longitudinal

2

section taken substantially on the indicated line 5—5 of Figure 3.

In the construction of the improvement as shown, the numeral 10 designates a circular plate or disc of any suitable strong, rigid material, such as metal, which constitutes the top of the stopper or plug unit and is hence sized to a diameter exceeding that of the passage or channel wherewith the unit is to cooperate so that 10 peripheral areas of the member 10 may engage against and lap over upon the end margin of such passage or channel. A relatively thick, annular skirt 11 of resiliently-yieldable material having a high frictional coefficient, such as rubber, is provided in a normal exterior diameter freely receivable within the channel or passage to be plugged and is fixedly secured at one end to and in concentric relation with one side of the member 10, said skirt 11 hence extending in 20 a suitable axial length perpendicularly from the plane of the member 10 whereupon it is centered. A suitable bail, or finger lift, 12 is hinged at its ends to the face of the member 10 opposite to that engaged by the skirt 11 and bridges diametrically of said member 10 to provide a lifting and manipulating facility in clearing relation with the central portion of said member, for reasons which will hereinafter appear.

The end of the skirt 11 remote from the member 10 is symmetrically hollowed and recessed to frusto-conical form and to taper in inward convergence toward the member 10, forming a thin, highly-flexible, circular edge or margin constituting the free end of said skirt, and to 30 intersect with the cylindrical inner wall of said skirt on a plane spaced substantially from the member 10, and a correspondingly frusto-conical block 13 of rigid material, such as metal, is formed to an axial dimension less than the axial depth of the skirt tapered recess and to diametric dimensions such as will permit engagement of the block thickness within the outer end of the skirt tapered recess without distortion of the normal cylindrical conformation of said 40 skirt, the conical surfaces of said block and skirt recess being correspondingly inclined for close engagement. A stem 14 is fixed in and axially of the block 13 to extend beyond and in perpendicular relation with the lesser diameter end of said block through a hole formed for its accommodation centrally of the member 10, the length of said stem 14 being sufficient to traverse the axial length of the unit with projection of its upper end above the member 10 when the block 50 13 is wholly disengaged from the tapered recess 55

of the skirt 11, as shown in Figure 2, and a retractile coil spring 15 surrounds the stem 14 between the member 10 and block 13 and is fixed at its appropriate ends to said block and member to normally draw the block 13 inwardly of the skirt 11 tapered recess with consequent diametric expansion of the skirt tapered walls, in the manner exemplified by Figure 1; such retraction of the block 13 inwardly of the skirt 11 projecting the free end of the stem 14 upwardly relative to the plate 10 within the oscillatory orbit of the bail 12.

It being expedient to provide means for retaining the block 13 against the tension of the spring 15 in separated, non-expanding relation with the skirt 11, a centrally-apertured, cylindrical insert 16, of rigid material, such as metal, is fitted and secured within the cylindrical base portion of the skirt 11 interior against the member 10 and in loosely-embracing relation with the spring 15, said insert 16 having an axial depth corresponding to the travel range desired for the block 13, and a succession of radial notches 17, illustrated as six in number, intersect the insert 16 in a uniform angular spacing to open through the face of said insert remote from the member 10 and hence toward the block 13. A series of pins 18 corresponding in number with the slots 17 is fixed to and rises perpendicularly from the lesser diameter face of and concentrically with the block 13 in a uniformity of angular spacing about the stem 14 such as positions each of the pins in said series for telescopic engagement of its upper end within one of the notches 17 when the block 13 is rotated relative to the insert 16 to bring said pins into registration with said notches. The pins 18 spacedly parallel the stem 14 and are alike in length in a dimension adequate to space the block 13 in separated, non-expanding relation with the skirt 11 when said pin free ends are engaged with lower face areas of the insert 16 between the notches 17, and to permit full expanding engagement of the block 13 within the skirt 11 when said pin free ends slidably enter said notches, whereby said block may be held against the tension of the spring 15 out of expanding engagement with the skirt 11 in one position of relative rotation between said block and the insert 16, while in another position of such relative rotation the spring 15 is free to act on and through the block 13 for expanding engagement of the latter within said skirt. To facilitate manipulation of the relatively adjustable unit elements, a radially-disposed finger 19 is fixed to the upper end of the stem 15 in position to spacedly overlie the member 10, and one end of said finger 19 is formed as an indicator adapted to register with one or another of three marks 20 formed on the upper face and adjacent the periphery of said member. As will be obvious, the center one of the three marks 20 indicates a position of finger 19, stem 14, and block 13 relative rotation wherein the pins 18 engage end faces of the insert 16 to hold said block in separated relation with the skirt 11, while the outermost marks 20 denote alternative, operatively-identical positions of finger, stem, and block relative rotation wherein the pins 18 may slidably enter the notches 17 for spring-induced expansion of the skirt 11 through the agency of the block 13, registration of the finger 19 with any one of the marks 20 giving an immediate visual indication of the corresponding movable element relationship. The finger 19, as is apparent, provides a manipulating facility wherethrough disengage-

ment of the pins 18 from their notches 17 may be effected against the tension of the spring 15 and subsequent rotation of the stem 14, block 13, and pins 18 may be had relative to the insert 16 for registration of the pin free ends with and to bear against end faces of said insert.

In the practical use of the improvement, the bail 12 is engaged by the fingers and pressure is applied through thumb or finger to the element 19 and thence through the stem 14 to depress said stem with its block 13 and pins 18 against the tension of the spring 15 and away from the member 10 until the ends of the pins 18 clear their notches 17, whereafter the element 19 is manually rotated to registration with the center one of the marks 20 and the pressure on said element is relieved to permit end abutment of the pins 18 against the insert 16 faces wherewith they are in registration, thus leaving the unit in the relationship of elements shown by Figure 2 wherein the spring 15 is extended and the block 13 is spaced from the skirt 11 to leave the latter in a normal, cylindrical condition of non-expansion. With the unit in normal, unexpanded condition of its skirt 11, said skirt is inserted and telescoped within the end of the passage or channel to be plugged, projecting margins of the member 10 closing over the annular end of such passage or channel, and thereafter slight pressure is manually applied to the finger 19 to slightly extend the spring 15 and clear the pins 18 relative to the insert faces, so that a slight subsequent rotation of the finger 19 to registration with one or the other of the outermost marks 20 followed by release of pressure acting on said finger permits contraction of the spring 15 to draw the block 13 with expansive effect upwardly within the skirt 11 while the free ends of the pins 18 slidably engage within the notches 17; such block-induced expansion of the skirt 11 wedging the resilient walls of the latter into close, tight, frictional engagement with the passage or channel. While certain minimum leakage may occur through the hole in the member 10 about the stem 14, it is to be noted that the block 13 itself seals against the tapered walls of the skirt recess and thereby closes off any channel through which leakage of consequence may occur when the unit is employed as a sink or lavatory drain plug.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

- An expansible stopper of the character described, comprising a rigid end plate, an annular skirt of resilient material fixed at one end to and concentrically of a face of said plate, an inwardly-converging, frusto-conical recess in the end of said skirt remote from said plate, a rigid, frusto-conical block coacting within and shiftable axially of said recess, a retractile spring interconnecting opposed faces of said plate and block interiorly of said skirt to normally draw the latter into skirt-expanding relation within said recess, and means interiorly of said skirt responsive to axial and rotational shift of said block relative to said skirt for holding said block against the tension of said spring in separated relation with said skirt and recess.
- An expansible stopper of the character de-

scribed, comprising an annular skirt of resilient material formed with an inwardly-converging, coaxial, frusto-conical recess opening through one of its ends, a rigid, frusto-conical block coacting within and shiftable axially of said recess, spring means interiorly of said skirt engaging said block to normally draw the latter into skirt-expanding relation within said recess, and means interiorly of said skirt responsive to axial and rotational shift of said block relative to said skirt for holding said block against the tension of said spring means in separated relation with said skirt and recess.

3. An expansible stopper of the character described, comprising an annular skirt of resilient material formed with an inwardly-converging, coaxial, frusto-conical recess opening through one of its ends, a rigid plate fixedly and concentrically closing the end of said skirt remote from said recess, a rigid, frusto-conical block coacting within and shiftable axially of said recess, spring means interiorly of said skirt engaging between said block and plate to normally draw the former into skirt-expanding relation within said recess, and complementary elements within said skirt reactive to axial shift and rotation of said block relative to said skirt for holding said block against the tension of said spring means in separated relation with said skirt and recess.

4. The organization according to claim 3, wherein said block fixedly carries an axially-projecting stem slidably and rotatably traversing said plate, and said spring means comprises a retractile coil spring fixed at appropriate ends to said block and plate in surrounding relation with said stem.

5. The organization according to claim 3, wherein said block fixedly carries an axially-projecting stem slidably and rotatably traversing and projecting outwardly beyond said plate furnished with a manipulating finger fixed to and radially of its end remote from said block, and said complementary elements comprise an annular spacer insert fixed to said plate within said skirt, angularly-spaced notches radially interrupting the face of said insert opposed to said block, and angularly-spaced, like pins fixedly outstanding from the inner face of said block in spaced parallelism with said stem for engagement of their free ends slidably within said notches and alternatively against face areas of said insert between said notches as determined by rotational adjustment of said block relative to said skirt.

6. In an expansible stopper of the character described having an annular skirt of resilient material formed with an inwardly-converging, coaxial, frusto-conical recess opening through one of its ends and a rigid, frusto-conical block coacting within and shiftable axially of said recess, a rigid plate fixedly and concentrically closing the end of said skirt remote from said recess, a retractile coil spring fixedly interconnecting opposed faces of said block and plate interiorly of said skirt to normally draw the former into

skirt-expanding relation within said recess, and complementary elements within said skirt reactive to axial shift and rotation of said block relative to said skirt for holding said block against the tension of said spring in separated relation with said skirt and recess.

7. In an expansible stopper of the character described having an annular skirt of resilient material formed with an inwardly-converging, coaxial, frusto-conical recess opening through one of its ends and a rigid, frusto-conical block coacting within and shiftable axially of said recess, a rigid plate fixedly and concentrically closing the end of said skirt remote from said recess, a stem fixedly projecting axially from said block slidably and rotatably engaging through said plate, a retractile coil spring fixed at its appropriate ends to opposed faces of said block and plate interiorly of said skirt in surrounding relation with said stem, and complementary elements within said skirt reactive to rotation and axial shift of said block relative to said skirt for holding said block against the tension of said spring in separated relation with said skirt and recess.

8. In an expansible stopper of the character described having an annular skirt of resilient material formed with an inwardly-converging, coaxial, frusto-conical recess opening through one of its ends and a rigid, frusto-conical block coacting within and shiftable axially of said recess, a rigid plate fixedly and concentrically closing the end of said skirt remote from said recess, a stem fixedly projecting axially from said block slidably and rotatably engaging through said plate, a retractile coil spring fixed at its appropriate ends to opposed faces of said block and plate in surrounding relation with said stem to normally draw said block into skirt-expanding relation within said recess and to project the stem end outwardly beyond said plate, a manipulating finger fixed to and radially of the stem end remote from said block, an annular spacer insert fixed to said plate within said skirt, angularly-spaced notches radially interrupting the face of said insert opposed to said block, and angularly-spaced, like pins fixedly outstanding from the inner face of said block in spaced parallelism with said stem for engagement of their free ends slidably within said notches and alternatively against face areas of said insert between said notches as determined by rotational and axial adjustment of said block relative to the skirt through the agency of said stem and finger.
